(57) **CLAIM**

The ornamental design for a baby car mirror, as shown and described.

DESCRIPTION

FIG. 1 is a perspective view of a baby car mirror showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of FIG. 1 in an unfolded state;

FIG. 9 is a schematic view of FIG. 9 when in use; and,

FIG. 10 is an exploded view of FIG. 9.

In the drawings, the broken lines depict portions of a baby car mirror that form no part of the claimed design. The vehicle seat shown in broken lines is for environmental subject matter only and forms no part of the claimed design.

1 Claim, 10 Drawing Sheets
